HARNESS CORD FOR LOOMS

Application filed August 10, 1929. Serial No. 384,328.

This invention relates to harness cords for looms and it is the general object of the invention to provide a durable form of attachment between a harness frame and a harness cord 5 formed of tiller cord.

Harness frames of looms are raised and lowered by means of one form or another of mechanism, such as heads, dobbies or cams, the lifting force being transmitted through 10 flexible connections which pass over pulleys or sheaves carried in the arches of the loom. It is an important object of my present invention to provide means including a head which is so clamped to the steel cable core of 15 the tiller cord as to be forced into the outer fibrous covering of the cord.

It is a further object of my present invention to remove a portion of the fibrous covering for the steel cable core and pass the same 20 through the head, wrapping the cable upon itself and then binding it tightly between the head and a portion of the tiller rod.

A still further object of my present invention is to provide improved connections between the cable and the head wherein the cable 25 is held within the periphery of the head so as not to project where it may have contact with adjacent cords or other moving parts of the loom.

With these and other objects in view which will appear as the description proceeds, my invention resides in the combination of parts hereinafter described and set forth in the 30 claims.

In the accompanying drawings, wherein a convenient embodiment of my invention is set forth,

Fig. 1 is a front elevation of a portion of a loom arch and harness frame having my 40 proved cord connected thereto,

Fig. 2 is an enlarged longitudinal section through the cord and head therefor,

Fig. 3 is a top plan view taken in the direction of arrow 3, Fig. 2,

Fig. 4 is a constructional view showing the relation of the parts before the head is closed,

Fig. 5 is a vertical section on line 5—5 of Fig. 3, on an enlarged scale, and

Fig. 6 is a vertical section on line 6—6 of 50 Fig. 4.

The loom frame or arch 10 has a pin 11 on which is mounted a plurality of harness sheaves, one being designated herein at 12. Harness frames 13, one of which is shown in Fig. 1, are raised and lowered by means of 55 mechanism not shown to form the sheds between the warp threads. Heretofore, it has been customary to effect raising and lowering of the harness frames through flexible connections such as small rope or leather straps. 60 Each harness frame is provided with a hook 14 which has connection with the flexible lifter.

In carrying my invention into effect I provide each harness frame with a strap or connector 20 formed of tiller cord, the same having a core 21 which is made up of several strands of flexible relatively fine steel wire. Surrounding this cable is a sheath of fibrous material 22 which resembles the ordinary cord 70 used in certain classes of looms.

I remove a portion of the sheath 22 and extend the core or cable through holes 23 and 24 formed in a head or connector 25 which is preferably sheet steel. The portion of the 75 connector between the holes is depressed as at 26 in Fig. 2. The end of the cable is passed first through hole 23, then over the depressed portion 26, and then through the other hole 23, being bent back under the depressed part 80 26 and wrapped around a portion of itself between the depressed part and the sheath 22, as designated at 27.

In Fig. 4 I have set forth one of the steps in the manufacture of my cord and connector, 85 the edges 28 and 29 being separated to define a substantially U-shaped cavity into which the fibrous covered end of the cable may extend, as in Fig. 6. After the steel core has been manipulated as described the straight end 30 90 will be extended along that part of the sheath 22 which lies in the cavity defined between the edges 28 and 29. By means of appropriate tools these edges are then closed so that the head assumes the cylindrical form shown 95 in cross section in Fig. 5.

The head is so proportioned that the edges 28 and 29 will force the end 30 into the fibrous sheath 22, as clearly shown on enlarged scale 100 in Fig. 5. It is by the construction set forth

in this latter figure that I am enabled to anchor the end 30 of the steel core securely and at the same time prevent the fibrous sheath from working loose and drawing out of the head. The head may have an extension 40 with a perforation 41 to receive the hook 14.

From the foregoing it will be seen that I have provided a very simple connection between a harness frame and tiller cord which includes a head having two holes through which the cord of the tiller top extends. The head has a depressed part between the holes over which the core extends, so that the latter will not project substantially beyond the periphery of the head. It will also be seen that by wrapping the cord around itself as at 27 I provide additional friction the effect of which is to provide a tight bind tending to prevent the core from working loose. Furthermore, the end 30 of the cable is so placed as to retain the sheath of fibrous covering 22.

Having thus described my invention it will be seen that changes and modifications may be made therein by those skilled in the art without departing from the spirit and scope of the invention and I do not wish to be limited to the details herein disclosed, but what I claim is:

1. In a connector for loom harnesses, a flexible cord having a fibrous sheath and a wire core, a head having holes through which the core extends, the core being wrapped on itself and being held embedded in the sheath by a portion of the head.

2. In a connector for loom harnesses, a flexible cord having a fibrous sheath and a wire core, the sheath being removed near the end of the cord and the core extending uncovered, a head through which the core extends, the end of the core lying between the head and sheath and being held embedded in the latter by the head.

3. In a connector for loom harnesses, a flexible cord having a fibrous sheath and a wire core, a sheet metal head having a cylindrical portion into which both the sheath and the core extend, said head having holding engagement with the core, the core being wrapped around itself and then extending between the sheath and the cylindrical portion of the head and being held embedded in the sheath by the head, whereby the sheath and end of the cable are held against relative movement with respect to each other.

4. In a connector for loom harnesses, a flexible cord having a fibrous sheath and a wire core, a head having a hollow cylindrical body provided with a pair of spaced openings, the part of the head between the openings being depressed, the wire core extending through the openings and along the depressed part of the head, so that said core lies substantially within the periphery of the head, the core being wrapped on itself and terminating within the head.

5. In a connector for loom harnesses, a flexible cord having a fibrous sheath and a wire core, a head having a hollow cylindrical body provided with a pair of spaced openings, the part of the head between the openings being depressed, the wire core extending through the openings and along the depressed part of the head, so that said core lies substantially within the periphery of the head, the core being wrapped on itself and terminating within the head, being held between the interior of the head and the sheath.

In testimony whereof I have hereunto affixed my signature.
